Letters Patent No. 87,944, dated March 16, 1869.

IMPROVED FLOOD-GATE.

The Schedule referred to in these Letters Patent and making part of the same.

To all whom it may concern:

Be it known that I, A B R A H A M L. K I N G, of Farmersville, Montgomery county, in the State of Ohio, have invented a new and useful Improvement in Flood-Gates; and I do hereby declare that the following is a full and exact description thereof, reference being had to the accompanying drawings, and to the letters of reference thereon.

Figure 1 represents a side elevation of my water-gate, with two of the posts broken away at the ground-line.

Figure 2 represents an edge view of the same, with a portion of the frame and posts broken away to exhibit the fastening.

In the accompanying drawings—

A B C denote three posts, which have mud-sills, D, secured by mortise and tenon, or spikes, to their feet, and braces, a a, may also be applied, as represented in the drawings, for the purpose of holding the posts firmly in the ground; and, for the same purpose, cross-pins, b, may be inserted in the bottoms of the posts.

The three posts may be set into the ground, in the bed of the stream of water, or creek, to bring the sill, E, down to the ground-line, represented at x x.

The plate F will be secured on the tops of the posts, in any substantial manner.

The gates, H, are constructed of square frames c c, d d, and boards e e, the latter being nailed upon one side only of the frames.

The gates H are suspended between the posts by bolts g, which pass through the posts and the frame-pieces c c of the gates, at a point about two-thirds of the length of the gates from their bottom thereof. The gates will freely open and close by a swinging motion, moving upon the bolts g as hinges.

The boards which cover the frames of the gates on one side, will be fitted up close to each other, to prevent flood-wood from becoming fastened therein.

A sufficient space is left open, between the bottom of the gates and the sill E, to admit the ordinary quantity of water to flow through it, which is supplied by the creek across which the gate is erected.

The upper surface of sill E is rounded off, to prevent sand and earth from lodging thereon.

Through the central post B there is a mortise, o, through which the metal bar p is inserted, and pivoted by a bolt, seen at i, fig. 2.

The pin k is inserted and secured in a hole in the end of the bar p, near the post B, to serve as a stop and fastening to the gates H.

The other end of bar p, which extends out at the front side of the gates H, is provided with a wooden block, M, which serves as a float.

N is a block, secured to post B, to prevent the gates from being opened in the opposite direction from that in which the water flows.

At the bottom of the gates, the two inner frame-pieces c c extend below the other parts of the gates, and at the rear side thereof these two frame-pieces c c are rounded off in the arc of a circle, for the purpose of allowing the pin k to move easily around and below them.

When the stream, or creek, is swollen by a flood, the water will cause the float M to be raised up, which movement will cause the bar p and pin k to occupy the position represented in fig. 2 in dotted lines, which will allow the gates to be opened by the flood; and when the flood subsides, the gates will close themselves by their gravity, and the block N and pin k will secure the gates from being pushed open by animals.

A single gate, or any connected number of gates, making a continuous fence, may be erected upon the same principle.

Having fully described my invention,

What I claim, and desire to secure by Letters Patent, is—

The swing-gate H and its fastening, consisting of the bar p, pin k, and float M, arranged to operate, in combination with each other, within the frame, consisting of the posts A B, plate F, and sill E, substantially as and for the purpose described.

In testimony whereof, I have hereunto set my hand, this 19th day of December, 1868.

A B R A H A M L. K I N G.
